(57) CLAIM

The ornamental design for a divided-toe shoe, as shown and described.

DESCRIPTION

FIG. 1 is a side perspective view of a divided toe shoe showing my new design;

FIG. 2 is a bottom perspective view thereof;

FIG. 3 is a bottom plan view thereof;

FIG. 4 is a top plan view thereof;

FIG. 5 is a right side elevational view thereof;

FIG. 6 is a left side elevational view thereof;

FIG. 7 is a front elevational view thereof; and,

FIG. 8 is a rear elevational view thereof.

The broken lines shown on the divided toe shoe represent thread stitching. The broken lines illustrating the symbol on the bottom of the shoe in FIGS. 2 and 3, the broken line of a square on the pull tab in FIGS. 4 and 5, and the symbol inside the triangle on the back of the heel in FIGS. 4 and 8 form no part of the claimed design.
